DESIGN FOR A BOTTLE

Jacob Englander, East Orange, N. J.

Application June 28, 1934, Serial No. 52,370

Term of patent 14 years

To all whom it may concern:

Be it known that I, Jacob Englander, trading as Federal Products Co., a citizen of the United States, residing at East Orange, in the county of Essex and State of New Jersey, have invented a new, original, and ornamental Design for a Bottle, of which the following is a specification, reference being had to the accompanying drawing, forming part thereof.

Figure 1 of the drawing is a front elevational view of the bottle; Figure 2 is a side view of the bottle; and Figure 3 is a bottom view of the bottle.

I claim:

The ornamental design for a bottle, as shown.

JACOB ENGLANDER.
